D. WILLIS.

Range.

No. 11,399.

Patented July 25, 1854.

UNITED STATES PATENT OFFICE.

DANIEL WILLIS, OF NEW YORK, N. Y.

APPARATUS FOR COOKING AND WARMING.

Specification of Letters Patent No. 11,399, dated July 25, 1854.

To all whom it may concern:

Be it known that I, DANIEL WILLIS, of the city, county, and State of New York, have invented a new and useful Improvement 5 in Heating Apparatuses for Cooking Purposes and for Supplying Heat for Warming Apartments; and I do hereby declare that the following is a full, clear, and exact description of the same, reference being had to the accompanying drawings, forming part of this specification, in which—

Figure 1, is a front elevation of the heating and cooking arrangements complete. 15 Fig. 2, is a vertical longitudinal section of the same through the line y, y , in Fig. 3. Fig. 3, is a horizontal section of the same, through the line x, x , in Fig. 2.

Similar letters of reference in each of 20 the several figures indicate corresponding parts.

The nature of my invention consists—

1st. In making the fire chamber in sections, and providing each section with a 25 broad horizontal ring flange which flanges project a considerable distance beyond the outer periphery of the vertical sections or rings which form the fire chamber or box, and serve for keeping said rings in place, 30 and as supports for them to rest upon, and also as receivers and suppliers, or conductors of heat to the hot air chamber, from whence it passes to the flue leading to the 35 apartment or chimney. This peculiar arrangement of the flanges, it will be evident effects several important objects.

1st. Increasing the heat to three times the amount of that which could be obtained were the flanges not employed, while the 40 additional space occupied and the expense incurred is very slight compared with other arrangements in use for the same purpose, and securing a perfect radiation of an additional quantity of heat for warming apartments without interfering materially with the cooking chambers or rendering the 45 kitchen too warm—it also avoiding the necessity of bringing the whole of the additional heating surface in direct contact with the fire, the flanges forming circular air 50 chambers and heating the air contained in them rapidly, as soon as which takes place the said air is forced off into the chimney or apartment flue as desired, and its place filled by a fresh supply of cold air from the air 55 passages in the side of the casing.

2nd. My invention consists in completely surrounding the outside and inside plates of the ovens which are arranged on top each other above the hot air chamber, with heated 60 flame, and hot air from the fire chamber, the said flame being introduced directly to the oven from the fire chamber or caused to have a circuitous passage and be slightly reduced in power before operating upon the 65 oven.

3rd. My invention consists in the employment of a damper for shutting off the intensely heated current and causing it to have a circuitous passage and become 70 slightly cooled before reaching the oven, thus regulating the action of the heat upon the oven.

It consists, 4th, in attaching to the back 75 of the heater a pipe or flue which connects with the chimney, and the hot air chamber and draws all the cold air from the chimney and supplies it to the fire, and causes it to draw well, and thus prevents the chimney 80 smoking.

5th. My invention consists in so arranging the hot air chimney flue and the flue for introducing the heated air into the apartment that one damper operated by a crank rod will serve for opening and closing the 85 openings of both, so that when the rod is moved in one direction, one passage will be opened, and the other closed, and vice versa.

My invention consists, 6th, in forming a 90 chamber in front of the front plate of the range for the purpose of receiving cold air and thereby reducing the temperature of said plate and consequently lessening the heat thrown off into the room.

It consists, 7th, in having a series of partitions placed around the inside of the fire chamber for the grate to rest upon, said partitions allowing of any depth of fire desired being made, for they allow of the grate being raised and lowered.

To enable others to understand more fully the construction and operation of my invention, I will proceed to describe it more minutely.

A, represents the casing which surrounds 105 the fire chamber, hot air chamber, and ovens.

B, is the fire chamber made in sections C, C, said sections being of ring form, and resting upon the horizontal circular flanges D, D, the projecting lips a, a , of the same serving to keep the sections C, C, in place as seen in Fig. 2. The flanges D, D, serve as 110

additional radiating surface for supplying heated air to apartments.

E is the grate. It has a series of ears b, b, which rest on the supports or partitions c, c, 5 these ears facilitating the operation of raising the grate from one partition to the other the partitions or projections c, c, allowing the grate to be raised or lowered as desired, they being placed on each section of the fire 10 cylinder.

F, is the chamber which receives the additional heat radiated by the flanges D, D. This chamber is supplied with fresh cold air from the register G, which keeps up the combustion of the fire; cold air is also admitted 15 through the passage d, and the flue H, leading from the apartment into which the hot air is introduced, the air introduced from the flue being supplied to the fire. I, is the flue 20 from the hot air chamber leading into the apartment. These flues are opened and closed alternately by the valve or damper f. This damper is operated by the crank rod g, it closing the flue I of the chamber, and 25 opening that J, when it occupies the position shown in red lines, Fig. 2, and closing the flue J, of the apartment and opening that I, of the chimney when it occupies the position shown in black lines in section. 30 When the flue f, occupies the position shown in red the hot air takes the course of the black arrows 1, and passes into the apartment, and when it occupies the position shown in black lines, the heated current 35 takes the course indicated by dotted red arrows and passes out through the chimney. This valve then serves as a regulator of the supply of heat to the apartment.

K, is the main oven placed above the hot 40 air chamber F, as seen in Fig. 2. This oven is completely surrounded by the heated flame, as plainly indicated, the flame circulating along or around the flues h, i, j, k, as it comes from the fire chamber, it being 45 introduced into said flues directly through the passage l, when the damper m, is opened, and when it is desired to have an intense heat introduced to the oven; but when said

damper is closed and it is not desired to have a very strong heat around the oven the 50 heated blaze is made to take a circuitous course around the passage n, before it reaches the oven, in doing which its effect is somewhat impaired or lessened. Thus the supply of heat to the oven can be regulated perfectly, the blaze and smoke find their exit through the pipes o, p, as shown clearly in the drawing. While the blaze is circulating in the flues around the oven the hot 55 air takes the course indicated by the full red arrows 2, 2, and aids in heating the outer plates forming the flues of the oven, and also serves for cooking pies or other articles placed in the top oven q, the heated air after performing its duty escaping 60 into the chamber R, through the passage S, as indicated by the red arrow 3.

S, is a door for keeping the heated air from passing into the kitchen. Under this door a draft passage r, is formed for fresh 70 air to pass into the chamber T.

U, is the chamber for admitting cold air to the front plates of the range, for the purpose of cooling said plates and thereby preventing too much heat being thrown into the 75 kitchen, holes u, u, being made in this chamber for air to rush into it.

V, is the inclined pipe or flue, which connects with the chimney and hot air chamber F, as seen in the drawing, Fig. 2. This 80 flue receives cold air from the chimney p, and introduces it into the fire chamber and causes it to draw well if its draft is not perfect.

What I claim as my invention and desire 85 to secure by Letters Patent, is:—

The arrangement, construction, and united operation of the several devices forming the cooking and warming apparatus herein shown, substantially as and for the purposes 90 set forth.

DANIEL WILLIS.
